CLAIM

The ornamental design for a leg, as shown and described.

DESCRIPTION

FIG. 1 is a front perspective view of a leg according to our new design.

FIG. 2 is a top view of the design of FIG. 1.

FIG. 3 is a bottom view of the design of FIG. 1.

FIG. 4 is a front view of the design of FIG. 1.

FIG. 5 is a rear view of the design of FIG. 1.

FIG. 6 is a right side view of the design of FIG. 1.

FIG. 7 is a left side view of the design of FIG. 1.

FIG. 8 is a left side orthogonal view of the design of FIG. 1.

FIG. 9 is a front orthogonal view of the design of FIG. 1.

FIG. 10 is a right side orthogonal view of the design of FIG. 1; and,

FIG. 11 is a rear orthogonal view of the design of FIG. 1 from the opposite side to FIG. 9.
